UNITED STATES PATENT OFFICE.

PETER J. TRIELLER, OF MILWAUKEE, WISCONSIN, ASSIGNOR TO A. MEINECKE & SON, OF SAME PLACE.

TOY GUN.

SPECIFICATION forming part of Letters Patent No. 285,368, dated September 18, 1883.

Application filed February 10, 1883. (No model.)

To all whom it may concern:

Be it known that I, PETER J. TRIELLER, a citizen of the United States, residing at Milwaukee, in the county of Milwaukee and State 5 of Wisconsin, have invented certain new and useful Improvements in Toy Guns; and I do hereby declare the following to be a full, clear, and exact description of the invention, such as will enable others skilled in the art to 10 which it appertains to make and use the same, reference being had to the accompanying drawings, and to letters or figures of reference marked thereon, which form a part of this specification.

15 My invention relates to improvements in that class of toy guns from which the projectiles are adapted to be thrown by a bow or elastic bands.

20 My improvements consist, first, in providing a receptacle, in connection with the barrel of the gun, adapted to contain a large number of balls; second, a device for automatically moving a single ball at a time for such receptacle to the bore of a gun as the propelling- 25 cord is sprung back in position to discharge the ball; third, a device for retaining the propelling-cord in rear of the ball preparatory to discharging the same; fourth, the device for preventing the ball when in the bore from 30 rolling of its own gravity therefrom; fifth, the general arrangement of the several elements of the device which co-operate together.

35 Figure 1 represents a perspective view of my invention. Fig. 2 is a longitudinal section, showing the position of an arm in position to receive a ball preparatory to throwing it up into the bore of the barrel. Fig. 3 is a longitudinal section, showing the position of said arm in the act of throwing the ball into 40 the bore of the barrel. Figs. 4 and 5 are detail views.

Like parts are represented by the same reference-letters.

45 A is the gun-barrel. B is the bore. C C are elastic straps. D is a connecting-rod by which the rear ends of the straps are connected. The front ends of the straps C are respectively connected to the bar E. The bar E is attached to the barrel by pivotal bolt F, which permits the 50 bar to be turned in line with and beneath the barrel A for convenience in carrying.

G is a receptacle for the balls A. The receptacle is attached to the barrel by the pivotal bolt I, which bolt permits the rear end of such receptacle to be turned from beneath the 55 barrel when being filled with balls.

J is a retaining-clasp, by which the receptacle is retained in line with the barrel when filled.

K is a spring, which spring is rigidly attached at one end to the barrel, at the side of the bore. The other end extends into the bore sufficiently to come in contact with the ball, the spring being adapted to prevent the ball from rolling of its own gravity from the barrel 60 of the gun, while it readily yields before the pressure of the ball when driven forward by the bow. A slide, L, is attached to the rod D and moves with it, striking against the balls, whereby they are projected from the gun. 65

The rear end of the slide L is provided with a hook, M, which engages with the retaining-arm N of the bracket O preparatory to discharging the gun. The arm N is disengaged from the slide L by drawing back upon the 70 trigger P when the slide L is thrown forward by the bow against the ball. The trigger P is pivoted to the gunstock R by pin Q. The rear end of the trigger is pressed downward by the spring S, whereby its front end is thrown upward, carrying with it the arm N, thus retaining said arm N in position to engage in slide L, as shown in Fig. 2. The bracket O is attached to the stock by a pivot, d'. The front 75 end of the bracket O is provided with a block, T, which is thrown upward as the arm N is thrown downward. Thus it is obvious that as the slide L is drawn back with the bow it presses down the arm N, whereby the block T is thrown upward, carrying with it one of 80 the balls as far as the lower line of the bore B, where the ball is retained by the spring U. The spring U is rigidly fastened to the side of the stock with a screw at W, where the rear 85 arm, a, of the spring presses the ball against the side of the groove b. When the first ball is thus held in the groove b by the spring, the trigger is drawn back, when the slide L moves forward without the ball. The slide L being 90 thus removed from above the arm N, said arm is free to move up into the recess d, when the block T is brought below the balls in the 95 100

that as the slide L is drawn back a second time the second ball is pressed upward against the first, whereby the first ball is thrown into the bore, as shown in Fig. 3, while the second ball is retained in said groove b by spring U, preparatory to being thrown into the bore of the barrel. Thus one ball after another is automatically brought into the bore and discharged with each forward movement of the bow.

If desired, the bow E may be substituted by an elastic bar, and the bands c may be substituted by a non-elastic cord.

Having thus described my invention, what I claim as new, and desire to secure by Letters Patent, is—

1. In a repeating bow-gun, the combination of trigger P, spring S, bracket O, block T, and slide L, said bracket O being provided with arm N, adapted to engage with said slide and receptacle and another ball rolls upon said block, as shown in Fig. 2. It is now obvious

retain the same in position to discharge the ball, said block T being adapted to move the balls from the receptacle to said bore in front 25 of said slide, substantially as and for the purpose specified.

2. In a repeating bow-gun, the ball-receptacle G, as secured to the stock by pivotal bolt I, and adapted to be turned from beneath the 30 stock when being supplied with balls, as set forth.

3. In a bow-gun, the combination of the barrel A, inflexible bar E, elastic straps C C, and pivotal bolt F, said bar E being adapted 35 to turn on said pivotal bolt in line with and beneath the barrel, substantially as and for the purpose specified.

In testimony whereof I affix my signature in presence of two witnesses.

PETER J. TRIELLER.
